UNITED STATES PATENT OFFICE.

ANDREW HOWARD, OF WILKINSBURG, PENNSYLVANIA.

DESIGN FOR A CHIMNEY.

SPECIFICATION forming part of Design No. 29,838, dated December 20, 1898.

Application filed November 26, 1898. Serial No. 697,462. Term of patent 7 years.

To all whom it may concern:

Be it known that I, ANDREW HOWARD, a citizen of the United States, residing at Wilkinsburg, in the county of Allegheny and State of Pennsylvania, have invented a certain new and useful Design for Chimneys for Incandescent Gas-Lights; and I do hereby declare the following to be a full, clear, and exact description of the invention, such as will enable others skilled in the art to which it appertains to make and use the same.

My invention has relation to a design for glass chimneys.

The accompanying drawing is a side view of 15 a glass chimney embodying my design.

The chimney consists of the cylindrical body

portion A, surmounted by the smaller cylindrical portion E, between which and the part A is the rounded shoulder B. The base of the body portion A is rounded to correspond with 20 the shoulder B, and below this is a narrowed cylindrical extension or neck F.

Having thus described my design, what I claim as new is—

The design for a chimney herein shown and 25 described.

In testimony whereof I affix my signature in presence of two witnesses.

ANDREW HOWARD.
